UNITED STATES PATENT OFFICE

122,167

DESIGN FOR A COSMETIC BAG

Joseph Levy, Brooklyn, N. Y.

Application June 12, 1939, Serial No. 85,462

Term of patent 3½ years

To all whom it may concern:

Be it known that I, Joseph Levy, a citizen of the United States, residing at 756 Crown St., Brooklyn, in the county of Kings and State of New York, have invented a new, original, and ornamental Design for a Cosmetic Bag, of which the following is a specification, reference being had to the drawing wherein.

Figure 1 is a front elevational view of a cosmetic bag with the flap partially broken away to expose the outer pocket, showing my new design;

I claim:

The ornamental design for a cosmetic bag, as shown.

JOSEPH LEVY.
